UNITED STATES PATENT OFFICE.

HERBERT H. WINSLOW, OF MOUNT TABOR, OREGON, ASSIGNOR TO
PACIFIC MANIFOLDING BOOK COMPANY, OF CARSON CITY, NE-
VADA, A CORPORATION OF NEVADA.

MANIFOLD SALES-BOOK.

No. 838,293.

Specification of Letters Patent.

Patented Dec. 11, 1906.

Application filed January 25, 1906. Serial No. 297,786.

To all whom it may concern:

Be it known that I, HERBERT H. WINSLOW, a citizen of the United States, residing at Mount Tabor, in the county of Multnomah and State of Oregon, have invented new and useful Improvements in Manifold Sales-Books, of which the following is a specification.

My invention relates to manifold sales books and pads, and especially books and pads of the type employing continuous zig-zag strips. These books are usually made by folding a continuous strip in zigzag formation with scorings at the folds to permit a leaf to be readily detached from the pad. The folded strip is detachably secured by some suitable means at one end, together with the carbon or transfer sheet, to a cover to permit any number of connected leaves to be drawn off without necessarily severing them from the pad. The opposite end of the pad is connected permanently to the cover in such fashion as to prevent the accidental disengagement of the pad from the cover, yet at the same time to permit the withdrawal and separation of one or more leaves without mutilating the leaf or leaves so withdrawn or detached.

The present invention has particularly to do with certain novel and economical means for fastening the leaves of a pad together in such fashion as not to interfere with the successive removal of the leaves of the pad, and which fastening means will have no sharp points for the operator to hurt his hand on.

The invention consists of the parts, and the construction and the combination of parts, as hereinafter more fully described and claimed, having reference to the accompanying drawings, in which

Figure 1 is a perspective view of a book, showing my invention. Figs. 2 and 3 represent a side elevation in section showing modifications thereof.

A represents a pad of usual construction, consisting of a continuous strip of suitably-printed paper folded in zigzag fashion. The pad may be secured to and protected by a cover of any appropriate form, material, or construction. I employ in practice a strip of tough flexible paper with a back portion 2, which may be reinforced by a suitable stiffening-piece 3. The strip 2 has a short flap 4 at one end to fold up over and protect the head or upper end of the pad and has a longer flap

or cover part 5 to fold up over the opposite end of the pad and protect the face of the pad. 55 A transfer or carbon sheet 6 is pasted or otherwise secured in any suitable manner to the flap 4 and is adapted normally to be interposed between the first and second, or original and duplicate, leaves of the pad. 6c

My invention resides, essentially, in the means for attaching one or both ends of the pad to the cover and back, where a cover or a cover and back are used or for holding the various leaf-sections of the pad together in 65 such manner that successive leaves may be withdrawn and detached without disturbing the remainder of the pad.

In Fig. 3 I have shown the invention applied to both ends of the pad. In Fig. 1 I 70 have shown the invention applied only to one end of the pad, the other end or head of the pad being detachably held to the cover and under the flap 4 by a rubber band 7, which encircles the head and is held in place by engagement in the lateral notches 8 in the flap 4. 75

The permanent fastening, above referred to, for the pad and cover or for the leaf-sections of the pad comprises one or more pieces of thread, twine, or like flexible, rough, 80 fibrous, expandable material 9, passed through the cover and stiffening-piece 3 and through the pad in the form of a stitch, said thread or twine or stitch being suitably anchored at the back of the cover or underneath the pad 85 to prevent its accidental pulling through the pad when a leaf is torn off, said stitch also having an end protruding beyond the face of the pad and adapted to unravel or expand immediately at its point of emergence from 90 the pad in such manner as to form an enlarged head larger than the diameter of the hole in the paper through which the stitch passes. This stitch being fibrous and more or less rough naturally has a certain frictional contact with the edges of the sheet around the stitch to hold all the leaf-sections of the pad together; but what is of more importance here is that the frizzled or unraveled end of the stitch beyond the body of the 95 pad offers a soft expanded cone-like head which will effectually hold the leaf-sections in position against accidental disarrangement and, moreover, offers no sharp points, such as are offered by wire staples, for the 100 operator's hand to be caught on and injured 105

- or to tear the overlapped flap of the cover. I do not wish to be limited to the number of such soft expansible stitches that I may employ, nor to the material used, nor to their position on the pad, nor to their use to one end only of the pad, nor to any particular means for anchoring the stitch to the pad or cover. A single stitch may be passed through one or both ends of the pad and knotted at the back, leaving half an inch, more or less, of the stitch projecting beyond the face of the pad to be unraveled and fluffed out. The stitch may be passed through a number of assembled books at one operation, the books afterward pulled apart a sufficient space to allow the stitch or stitches to be cut between each book, and one end of each stitch for each book being knotted or otherwise anchored at the back with a sufficient length of free end for unraveling and locking purposes at the front of the pad. A stitch of this sort cheapens manufacture; besides, it produces a book free from the objections of wire or other metallic stitches.
- Manifestly a pad need not necessarily be made of a continuous zigzaggedly-folded strip, for the same principle is applicable to the holding together in pad form of a bunch of loose leaves.
- Having thus described my invention, what I claim, and desire to secure by Letters Patent, is—
1. A pad having its leaves fastened together by a U-shaped member passed therethrough, the extremities of said member being on the face side of said pad and being of a soft expansible character.
  2. A pad having its leaves fastened together by a soft expansible device passing through the leaves of the pad and anchored at the back of the pad, and having an expansible head portion on the face side of the pad.
  3. A pad having its leaves held together by a thread of soft expansible material, said thread suitably anchored to prevent its withdrawal from the pad, and having a free fluffy end operating as a head to prevent the accidental separation of the leaves of the pad but permitting the ready intentional removal of successive leaves.
4. A pad having its leaves held together by a fastener of flexible expansible material, said fastener anchored at the back of the pad and having a contractible head portion engaging the top sheet of the pad.
5. A pad having its leaves held together by a fastener passing through coinciding perforations in the leaves, said fastener being of flexible fibrous material and having frictional contact with the edges of the leaves through which it passes, said fastener anchored to prevent its withdrawal from the pad, and having a free expansible end on the face side of the pad.
6. In a sales-book, a pad, a cover of flexible material having an end flap to fold over the head of the pad, said end flap having lateral notches, a carbon sheet secured to said end flap, a rubber band seated in said notches and encircling the head of the pad and holding the latter detachably to the cover, and a member having a soft contractible head on the face side of the pad, said member being passed through the opposite end of the pad and cover and permanently securing the pad to the cover and permitting the ready removal of successive leaves of the pad.
7. A pad having its leaves held together by a fastener passed through the leaves of the pad and provided with a soft contractible head engageable with the top sheet of the pad.
- In testimony whereof I have hereunto set my hand in presence of two subscribing witnesses.

HERBERT H. WINSLOW
